UNITED STATES PATENT OFFICE.

MAX ROCKSTROH, OF KLEIN SEDLITZ, NEAR PIRNA, GERMANY.

INKING MECHANISM FOR PLATEN PRINTING-PRESSES.

1,139,584.

Specification of Letters Patent. Patented May 18, 1915.

Application filed January 26, 1914. Serial No. 814,590.

To all whom it may concern:

Be it known that I, MAX ROCKSTROH, manufacturer, subject of the Kingdom of Saxony, in the German Empire, residing at 5 Villa Lützow, Klein Sedlitz, near Pirna, Germany, have invented certain new and useful Improvements in Inking Mechanism for Platen Printing-Presses, of which the following is a specification.

10 Hitherto, in connection with double acting inking devices for platen printing presses, it has been usual that the inking rollers, after the first inking of the form bed, travel into contact with two rotating distributing rollers, below the form bed, whereby the ink still adhering to the inking rollers and together with fresh ink brought down by the rider rollers, is evenly spread prior to the second inking of the form bed. The inking 15 rollers roll rapidly over these distributing rollers, so that the time available for distributing the ink is comparatively short.

The object of my invention is to provide an arrangement whereby a longer period of 20 distribution is obtained, resulting in a better inking of the form bed.

The invention is illustrated in the accompanying drawing, in which—

Figure 1 is a front view of the inking 30 mechanism, and Fig. 2 is a side view of the same.

The inking rollers *a*, with the rider rollers *b*, are supplied with fresh ink by the ductor rollers *c* and *d*. In the course of the 35 descent of the inking rollers *a*, the form bed *e* is inked and the rollers *a* then come into contact with an endless web *g* which travels over two driven drums *f*, and the tension of which is regulated by means of an adjustable 40 roller *h*, the latter also serves to rub the ink

on the web. The inking rollers *a* remain for a comparatively long period in intimate contact with the web *g*, so that a uniform distribution of ink on all the inking rollers, 45 riders and web is insured. During the upward movement the form is inked with the freshly rubbed ink in the well known manner.

Having now particularly described and ascertained the nature of my said invention 50 and in what manner the same is to be performed, I declare that what I claim is:—

1. In platen printing presses having a double acting inking device, in combination with the inking rollers, their riders and ductors, an endless web intimately contacting with said inking rollers, means for guiding said web, and means for tensioning the same and for uniformly distributing ink over its 55 face for distribution over the inking rollers 60 during their contact therewith.

2. In platen printing presses having a double acting inking device, in combination with the inking rollers thereof, their riders and ductors, an endless web intimately contacting with said inking rollers while passing the same, revolving drums for guiding 65 said web past said rollers, and an adjustable tension- and inking roller adapted to regulate the tension of said web, and to uniformly distribute ink over the same for distribution over the ink rollers during their contact with said web.

In testimony whereof I have hereunto set my hand in presence of two subscribing witnesses.

MAX ROCKSTROH.
